(57) **CLAIM**

The ornamental design for step-on foot file device, as shown and described.

DESCRIPTION

FIG. 1 is a perspective view of a step-on foot file device, in accordance with an embodiment of the claimed design;

FIG. 2 is a top plan view thereof;

FIG. 3 is a bottom plan view thereof;

FIG. 4 is a front elevation view thereof;

FIG. 5 is a rear elevation view thereof;

FIG. 6 is a side view thereof;

FIG. 7 is an opposing side view of FIG. 6;

FIG. 8 is the perspective view of FIG. 1 with a roller body coupled thereto, the roller body shown in broken lines and forming no part of the claimed design; and,

FIG. 9 is an exploded perspective view thereof, showing an open, extended tray.

The portions of the step-on foot file device shown in broken lines form no part of the claimed design.

1 Claim, 8 Drawing Sheets
